UNITED STATES PATENT OFFICE.

SAMUEL HIRSCH, OF NEW YORK, N. Y.

SNAP.

1,326,055.

Specification of Letters Patent. Patented Dec. 23, 1919.

Application filed September 18, 1919. Serial No. 324,388.

To all whom it may concern:

Be it known that I, SAMUEL HIRSCH, a citizen of the United States, and a resident of the city of New York, borough of Bronx, in the county of Bronx and State of New York, have invented a new and Improved Snap, of which the following is a full, clear, and exact description.

Various means have been constructed with a view of providing an ornamental member for securing together the two ends of a chain, such as a lavallière, or conveniently securing together the ends of a cord adapted to receive beads, pearls, etc.

Known constructions have heretofore proved slightly impractical, for the reason that the grasped portion of the snap had to be inserted in a certain manner into the grasping portion thereof to effectively lock the two parts together. Another objection which inventions of this nature have presented is that of the likelihood of breakage occurring, which in the case of a light chain would almost invariably result in the loss of the chain and any article appended thereto, as the snap would readily open.

My invention aims to provide a snap in which the grasped portion may be inserted in the grasping portion in any manner desired, which shall be ornamental, and yet so simple in construction as to prohibit any danger of breakage occurring.

Reference is had to the attached sheet of drawings which illustrates practical embodiments of my invention, and in which—

Figure 1 illustrates a side view of the grasped and grasping portions of the snap separated one from the other and with the two ends of a chain attached thereto;

Fig. 2 is an enlarged sectional view on line 2—2 of Fig. 3;

Fig. 3 is a sectional view taken along line 3—3 of Fig. 2;

Fig. 4 is an enlarged elevational view of the member associated with the grasping portion, and

Fig. 5 is a sectional view, similar to Fig. 3, of a slightly modified form of snap.

In all these views like reference numerals 50 designate similar parts, and the reference numeral 1 indicates the grasping member which has conveniently associated with its lower end an eyelet to which a chain, thread, etc., may be attached. The grasping member 1 may include, as is clearly shown in

Fig. 3, two half sections 2 and 3 which have interposed between them a U-shaped link 4 the outer end of the arms of which are bent inwardly one toward the other, as indicated by the reference numeral 5. In this connection it will be noted that the outer ends of the arms of the U-shaped member 4 terminate at a point short of the end of the half sections 2 and 3, which provides an opening at the outer end of the grasping member.

The grasping member includes a V-shaped, resilient member 6 one of the arms of which is slightly shorter than the other, the end of the longer arm being bent toward the shorter arm and partially overlying the same, as indicated by the reference numeral 7. In this connection it will be noted that the portion 7 of the grasping member has its outer edge shaped so as to conform to 70 the contour of the outer end of the half sections 2 and 3, and is further provided with a conveniently attached eyelet adapted to receive the end link of a chain, or a cord.

The outer end of the shorter arm of the 80 V-shaped grasped member 6 is bent outwardly, as indicated with the reference numeral 8, and the longer arm is provided with an outstanding portion 9 occupying the same relative plane as the portion 8 of the shorter arm, both such projection and arm being provided at their outer ends with roughened thumb pieces 10 conveniently attached. The V-shaped member is further formed in such a manner that notches are 85 provided in its outer edge adjacent and below the outwardly-bent portion 8 and the outstanding portion 9.

It will now be seen that the grasped portion may readily be inserted between the 95 half sections 2 and 3 of the grasping portion 1 and firmly pressed therein, which will result in the arms of such V-shaped member 6 being moved one toward the other until the notches formed in such latter member 100 reach a point adjacent the inwardly-bent arms of the U-shaped link, whereupon they will snap outwardly, as clearly shown in Fig. 2, and prevent any accidental removal of the grasped member with respect 105 to the grasping member.

However, should it be desired, the V-shaped member may readily be disengaged from the grasping member 1 upon the thumb piece 10, the outer surface of which, as 110

aforestated, has been roughened, being pressed together and the V-shaped member withdrawn.

Obviously, in some instances it might prove impracticable, as well as expensive, to provide a U-shaped member 4, and for this reason, reference being had to Fig. 5, I may provide my half sections 2 and 3 with integral inwardly-extending projections 11 which will serve the same purpose as the inwardly-bent outer ends 5 of the U-shaped member 4.

Further, it will be appreciated that by virtue of the construction illustrated the V-shaped member may be inserted with its shorter arm toward either side, as the case may be, without in the least affecting the functioning of the snap, which will operate just as efficiently in either position.

Obviously, any number of modifications may be made without in the least departing from the scope of my invention.

I claim:

1. A snap including a grasping and a grasped member, which grasping member comprises two half sections formed with a space therebetween at one of their ends, inwardly-extending projections adjacent the ends of such space, said grasped member including a V-shaped resilient member formed with notches adjacent its outer end, said notches being adapted to be engaged by the projections within the grasping member.

2. A snap including a grasping and a grasped member, which grasping member comprises two half sections formed with a space therebetween at one of their ends, inwardly-extending projections adjacent the ends of such space, said grasped member including a V-shaped resilient member hav-

ing one of its arms longer than its opposite arm, the longer of said arms being bent so as to extend toward and partially overlying the shorter arm and conforming to the contour of the spaced ends of the half sections, 45 the outer edges of the arms of the V-shaped member being formed with notches adapted to be engaged by the projections within the grasping member.

3. A snap including a grasping and a 50 grasped member, which grasping member comprises two half sections formed with a space therebetween at one of their ends, inwardly-extending projections adjacent the 55 ends of such space, said grasped member including a V-shaped resilient member having one of its arms longer than its opposite arm, the longer of said arms being bent so as to extend toward and partially overlying the shorter arm and conforming to the contour 60 of the spaced ends of the half sections, the outer edges of the arms of the V-shaped member being formed with notches adapted to be engaged by the projections within the grasping member, the outer end of said 65 shorter arm being bent upwardly, the longer arm being provided with an outwardly-extending projection in the same plane in which the shorter arm terminates, and thumb pieces secured to the ends of such projection 70 and arm respectively.

4. A snap including two half sections, a U-shaped member interposed between such half sections and having the outer ends of its arms bent inwardly one toward the other, 75 and a grasped member formed with notches adapted to be engaged by the ends of said inwardly-bent arms.

SAMUEL HIRSCH.
